POLISHING OR LAPPING MACHINE

John Gordon Kaveny, Montclair, N.J.

Application December 15, 1948, Serial No. 65,439

4 Claims. (Cl. 51—50)

1

This invention relates to improvements in polishing or lapping machines of the type used in finishing dies, and, more especially, for polishing the die apertures of tungsten carbide wire drawing and similar dies.

The invention has for an object to provide an improved construction of polishing or lapping machine of the type having opposed head and tail stocks, wherein the tail stock includes means to support a rotatable spindle provided with a chuck for operatively coupling a lapping tool or pin therewith, and further including novel means for reciprocating the spindle supporting means with oscillatory movement, together with means for regulating the bearing tension of the operated lapping tool or pin upon the work, whereby to produce a constant rubbing contact of said lapping tool or pin with the surface of the work under treatment, which contact is accompanied by tensional thrust of the former toward the latter of desired degree.

Other objects of the invention, not at this time more particularly enumerated, will be understood from the following detailed description of the same.

An illustrative embodiment is shown in the accompanying drawings, in which:

Fig. 1 is a side elevational view of the polishing or lapping machine according to this invention; Fig. 2 is a transverse vertical sectional view, taken on line 2—2 in Fig. 1; and Fig. 3 is a fragmentary side elevational view, with parts broken away and parts in longitudinal section.

Similar characters of reference are employed in the hereinabove described views, to indicate corresponding parts.

Referring to the drawings, the reference character 10 indicates the base of the machine, the same being preferably supported by legs 11. Mounted on one end of the base 10 is the usual head stock 12 with which a polishing or lapping machine of the kind stated is provided. Rotatably mounted in the head stock 12 is a head stock spindle 13 which is provided with collet 14 in which the die or other work 15 to be treated is clamped. The collet 14 is operated by a draw-in bar 16 having a handle 17 for manipulating the same. Fixed on said spindle 13 is a step pulley 18, over which can be run a power transmission belt (not shown) by which the machine is operated. Also affixed on the spindle 13 is a drive pulley 19.

Journalized in the base 10, to extend longitudinally therethrough, is a countershaft 20. Fixed on one end of said countershaft 20 is a driven

2

pulley 21 over which runs a drive belt 22 which is driven by the drive pulley 19.

Slidably mounted on the base 10, subject to adjustment toward and from the above described head stock mechanism, is the carriage member 23 of the tail stock structure of the machine. Said carriage member 23 can be secured to the base 10, in adjusted position thereon, by a clamp element 24 which cooperates with said base 10, and which is adapted to be actuated by an eccentric cam 25 having a hand lever 26 by which it is manipulated, all in manner known to the art. Extending rearwardly from the carriage member 23 is a bracket arm 27, in which is mounted a transverse pivoting shaft 28. Pivotedly supported by the pivoting shaft 28 is a tail stock frame which is adapted to be oscillated in vertical plane toward and from the head stock mechanism. Said frame comprises a pair of side plates 29 disposed to straddle the bracket arm 27 so as to be respectively supported by their lower ends upon the respective ends of said pivoting shaft 28. Pivotedly supported in connection with the upper end of the tail stock frame is a longitudinally directed bearing member 30. Affixed on the rearward end portion of said bearing member 30 is a yoke 31 having oppositely extending transverse trunnions 32 which respectively pivotally engage in respective upper end portions of the side plates 29 of the tail stock frame, whereby to pivotally support the bearing member for up and down oscillatory movement in vertical plane. Rotatably supported by the bearing member 30 is a hollow spindle driving shaft 33, in which is adjustably secured an axially extending spindle 34. Said spindle 34 is provided at its forward end with a chuck 35 for operatively coupling a lapping tool or pin 36 to the spindle. Fixed on the rearward end of the countershaft 20 is a drive pulley 37, and fixed on the rearward end of the spindle driving shaft 33 is a driven pulley 38. A transmission belt 39 runs over the pulleys 37 and 38, whereby to rotate the shaft 33, spindle 34 and lapping tool or pin 36. Since pulley 38 is on the outer or rearward end of drive spindle shaft 33, belt 39 will exert a downward pull on said shaft and thereby counterbalance the weight of the inner portion of bearing member 30 and the parts supported thereby.

Means is provided for oscillating the tail stock frame. This means comprises a rearwardly projecting rocker arm 40. Said rocker arm is affixed to and between the side plates 29 of the tail stock frame by means of cross pins 41 which extend through these parts. The rocker arm 40 thus

provides a unitary part of the tail stock frame, and is so related thereto as to extend from a point intermediate the lower end and upper ends thereof. Fixed on the countershaft 20 is an eccentric cam 42 which is disposed below the rearwardly projecting free end portion of the rocker arm 40. Threaded downwardly through the free end portion of the rocker arm 40 is a cam follower stud 43 which bears upon the eccentric cam 42. Said cam follower stud 43 may be adjusted relative to the eccentric cam 42 so as to predetermine the limit of the back stroke of the tail stock frame. Cam 42 is axially wide and substantially parallel to the direction of adjustment of carriage member 23, so follower stud 43 is free to slide axially on the cam periphery during any carriage adjustment without affecting the angular position of rocker arm 40. Means is provided to cause the rocker arm 40 and its cam follower stud 43 to follow the eccentric cam 42. The means for this purpose comprises a longitudinally disposed, end-wise open housing member 44 which is provided in connection with the upper part of the carriage member 23 of the tail stock structure. Fixed in connection with and so as to extend through said housing member 44 is a barrel 45 having a rearwardly open bore 46 and a forward end wall 47. Slidably movable in said bore 46 is a thrust pin 48, the same having a tail piece 49 of reduced diameter which extends outwardly through the closed forward end 47 of the barrel 45. Tail piece 49 is in the form of an elongated screw that has screw-threaded engagement with thrust pin 48 and has an external manipulating head but is freely slideable as well as rotatable in the closed forward end 47 of barrel 45. Tail piece 49 thus serves as guiding means for spring 50 and limits outward thrust of thrust pin 48. Engaged between the end wall 47 of the barrel 45 and the inner end of the thrust pin 48 is a compression spring 50. Said compression spring 50 yieldably urges the thrust pin 48 against the fixed end of the rocker arm 40, whereby to swing the tail stock frame in clockwise direction, and thus the free end of the rocker arm 40 with its cam follower stud 43 downwardly, to cause the latter to maintain contact with the surface of the eccentric cam 42.

Means is provided for yieldably inducing a down swinging movement of the bearing member 30 and the spindle 34 and lapping tool or pin 36 which is supported by said bearing member 30, whereby to produce a constant bearing contact or thrust of the operative end portion of the lapping tool or pin 36 against the surface of the die 15 under regulatable tension, while said tool or pin is rotated and reciprocated by the cam actuated movement of the tail stock frame. The means for causing the lapping tool or pin to tensionally bear against the surface of the die under treatment comprises a pull spring 51, the lower end of which is anchored to the carrier member 23. Affixed to the bearing member 30, forwardly of its pivotal connection with the tail stock frame, is a laterally projecting bracket 52 which is provided with a slotted or bifurcate free end portion. Connected with the upper end of the pull spring 51 is a screw-threaded coupler element 53, which is disposed to extend upwardly through the slotted or bifurcate free end portion of the bracket 52. Threaded onto the free end portion of the coupler element 53 is an adjusting nut 54 which bears upon the upper face of said bracket 52. It will be obvious that by turning the adjusting nut 54 in proper direction, the down pulling tension of the pull spring 51 may be op-

tionally increased or decreased, whereby to regulate the degree of tensional down thrust force by which the lapping tool or pin 36 is caused to bear upon the surface of the die 15 under treatment thereby.

Preparatory to operation of the machine, the spindle 34 is longitudinally adjusted and so fixed to its driving shaft 33 as to operatively enter and engage the lapping tool or pin 36 in the aperture of the die 15, the surface of which is desired to be polished or lapped.

In the operation of the machine, when power is applied to the pulley 18, the head stock spindle 13 and collet 14 are rotated so as to rotate the die 15 which is affixed to the collet. Power is transmitted from the head stock spindle 13, by the pulley and belt transmission 19, 22 and 21, to the countershaft 20. Power is transmitted from the countershaft 20, by the pulley and belt transmission 37, 38 and 39, to the spindle driving shaft 33 of the tail stock structure, whereby the spindle 34 and lapping tool or pin 36 is rotated. Also the countershaft 20 rotates the eccentric cam 42.

The rotated eccentric cam 42 operating upon the rocker arm 40, in conjunction with the spring actuated thrust pin 48, produces back and forth oscillation of the tail stock frame, whereby the bearing member 30 is longitudinally reciprocated, together with the rotated spindle 34 and lapping tool or pin 36, relative to the rotated die 15. Due to this, the contacting surfaces of the lapping tool or pin 36 and the die aperture are not only relatively moved rotatively but also longitudinally, whereby the contacting surfaces are constantly shifted with uniform rubbing or lapping effect upon the entire surface area of the die aperture.

Due to the downward tensional thrust imparted to the rotated and reciprocated lapping tool or pin 36 relative to the die aperture surface, not only is the former maintained in constant rubbing contact with the latter, but at the same time subject to a desired selected degree of rubbing pressure. Since the tension of downward thrust of the lapping tool or pin is subject to regulation, by adjustment of the tension of pull spring 51, the bearing pressure of said tool or pin upon the die aperture surface can be effectively maintained at the desired selective amount of pressure force found to be of best advantage for accomplishment of the polishing or lapping operation.

From the above it will be understood that a very efficient means is provided for relatively moving the mutually engaged surfaces of a lapping tool or pin and the work both rotatively and reciprocably, while at the same time assuring both constant engagement of said surfaces without interruption or chattering as well as with a desired degree of rubbing pressure.

Having now described my invention, I claim:

1. In a polishing or lapping machine of the kind described having a head stock provided with means for rotating the work and a driven countershaft, a tail stock structure comprising a carriage member mounted for manual sliding adjustment substantially parallel to the axis of said work rotating means, securing means for said carriage member, a tail stock frame pivotally supported by said carriage member for oscillation on an axis substantially perpendicular to the direction of carriage member adjustment, said tail stock frame having a rocker arm, a cam driven by said countershaft operative upon the rocker arm to oscillate said tail stock frame, spring actuated means urging said rocker arm in following

relation to said cam, a bearing member pivotally supported by said tail stock frame on an axis substantially parallel to the pivotal axis of said tail stock frame, a spindle driving shaft journaled in said bearing member on an axis substantially perpendicular to the pivotal axis of said bearing member, countershaft driven transmission means for rotating said spindle driving shaft, a spindle extending from and driven by said driving shaft, means for coupling a lapping tool to said spindle, and spring means cooperative with said bearing member, said spring means being adapted to down swing said bearing member, spindle and lapping tool whereby to effect rubbing pressure of the latter upon the work.

2. In a polishing or lapping machine as defined in claim 1, the construction and arrangement of parts, wherein the cam for oscillating the tail stock frame is rotatable on an axis substantially parallel to the direction of adjustment of the carriage member and has an axially wide peripheral face which may be traversed axially by the rocker arm in its following relation to said cam during adjustment of the carriage member.

3. In a polishing or lapping machine as defined in claim 1, the construction and arrangement of the cam follower means, wherein a screw threaded follower stud is adjustably engaged with the rocker arm of the tail stock frame for movement toward and away from the countershaft driven cam to permit predetermination of the limit of the backstroke of the said tail stock frame.

4. In a polishing or lapping machine as defined in claim 1, the construction and arrangement of parts, wherein the work rotating means and countershaft are disposed with their rotational axes substantially horizontal and in the same vertical plane, and wherein the countershaft driven means for rotating the spindle driving shaft comprising a driving pulley affixed to the countershaft, a driven pulley affixed to the outer end of the spindle driving shaft, and a belt connecting both of said pulleys for power transmission and to counterbalance the weight of the inner end portion of the bearing member and supported parts.

JOHN GORDON KAVENY.
